[57] **CLAIM**

The ornamental design for a bottle cap, as shown and described.

DESCRIPTION

FIG. 1 shows a front perspective view of my new design; FIG. 2 shows a side elevation view thereof with all other side elevation views being a mirror image thereof; FIG. 3 shows a top plan view thereof; and, FIG. 4 shows a side elevation view of the bottle cap of FIG. 1 mounted on a bottle.

The broken line showing a bottle is for illustrative purposes only and forms no part of the claimed design.

The bottom and interior of the bottle cap form no part of the claimed design.
